UNITED STATES PATENT OFFICE.

CLARENCE S. WICKES, OF MERCHANTVILLE, NEW JERSEY, ASSIGNOR TO VICTOR TALK-
ING MACHINE COMPANY, A CORPORATION OF NEW JERSEY.

PACKING AND SHIPPING BOX OR CASE.

Application filed March 5, 1921. Serial No. 449,818.

To all whom it may concern:

Be it known that I, CLARENCE S. WICKES, a citizen of the United States, and a resident of the borough of Merchantville, in the 5 State of New Jersey, have invented a certain new and useful Improvement in Packing and Shipping Boxes or Cases, of which the following is a full, clear, and exact disclosure.

10 My invention relates to cases or boxes in which articles may be packed and safely shipped, and my invention particularly relates to those cases or containers which are preferably made out of sheet material, such as cardboard or box-board, and which are provided with a tray of similar sheet material adapted to securely hold and protect from injury, the article fitting therein, the tray being shaped and adapted to closely fit 15 within the outer casing or box. More particularly, my invention relates to cases or boxes in which one of at least two different types or kinds of articles may be placed without any change in the construction of 20 the packing box.

25 The object of my invention is to provide an inexpensive easily constructed packing and shipping box or case in which one of more than one kind or type of article may be fitted with equal facility, to avoid the necessity of making a separate or different tray or container for each different kind or type of article.

30 Further objects of my invention are to 35 so construct the outer casing and tray to be fitted therein, that the strong substantially unbreakable parts of the article, such as the metallic casing of a sound box, when fitted within the tray and placed in the outer box 40 or container, gives strength and rigidity to the entire package, while at the same time, any delicate easily injured parts of the article, such as the diaphragm, stylus bar and stylus bar mounting, are kept spaced 45 away from and out of contact with any part of the shipping box or case, or of the tray contained therein, and are thus protected from injury. Other objects of my invention 50 will appear in the specification and claims below.

In the drawing forming a part of this specification and in which the same reference characters are employed throughout the various views to designate the same

parts, Fig. 1 is a perspective view of my new 55 and improved packing and shipping box or case with the tray removed from the outer box or casing and in position to be inserted into the outer box or casing.

Fig. 2 is a longitudinal sectional view of 60 the shipping box and tray assembled with one kind or type of sound box mounted or packed therein; and

Fig. 3 is a similar view of the tray alone 65 with another kind or type of sound box mounted or packed therein and ready to be inserted into the outer box or casing of the package.

The outer box or casing 1 is a rectangular box, preferably made of cardboard folded 70 in any suitable or appropriate manner, and preferably provided with an opening 2 at one end thereof which may be closed by first folding down the two side flaps 3—4 and then folding up the large end flap 5 provided 75 with a narrow extension flap 6 adapted to fit over the top edges of the side flaps 3—4 and under the top side of the box or casing 1. The top of the box or casing 1 is preferably provided with a semicircular 80 recess 7 to facilitate the withdrawal of the narrow extension flap 6 to open the outer box or container 1, and to facilitate the removal of the tray 8 from the outer casing 1 85 as will be referred to again below.

The tray 8 is preferably made from a sheet of card-board or box-board, or other sheet material, first cut into a blank and suitably scored for bending and folding. The completed tray comprises two parallel spaced 90 rectangular tray members 9 and 10, with the web 11 connecting said members along an edge thereof. The tray member 9 is preferably provided around the three free edges thereof with an outwardly extending perpendicular flange 12, made by bending up the integral flaps 13, 14 and 15. The flap 15 is preferably provided with short or small integral flaps or extensions 16—16 which are preferably respectively glued or otherwise 95 rigidly secured to the side flaps 13 and 14 to form the said rigid outwardly extending flange 12.

The other tray member 10 is similarly provided with an outwardly extending flange 105 17, similarly formed by bending up the side flaps 18 and 19 and the end flap 20 similarly provided with similar small extensions or

flaps 21—21 which are then similarly respectively secured by glue or otherwise, to the inside of the side flaps 18 and 19.

In this way the two tray members 9 and 10 are provided along the three free edges thereof with rigid flanges extending outwardly and serving, among other things, to stiffen the whole structure, and to hold the article placed therebetween spaced from the walls of the outer container. The web 11 in addition to serving to secure together the two tray members, may also form a common flange for both tray members tending to stiffen and make rigid the edges of the two tray members that are integrally connected together thereby.

To hold the article and prevent its displacement each tray member is provided with an elongated opening or aperture 20 which consists of a circular portion communicating with a radially extending parallel-sided slot portion narrower in width than the diameter of the circular portion, the aperture thus formed being somewhat of the shape of a keyhole. One tray member 9 is provided with a keyhole shaped structure 22 having a circular portion 22^a and a parallel sided portion 22^b communicating therewith, the aperture 22 being preferably disposed longitudinally of the tray member 9. Similarly, the other tray member 10 is provided with a similar keyhole shaped aperture 23, comprising the circular portions 23^a and the parallel sided slot portion 23^b. The circular portions 22^a and 23^a of the apertures 22 and 23 are in axial alinement with each other when the trays are placed one over the other, but they are preferably of different diameters and the edges thereof are adapted respectively to fit around snugly and hug the cylindrical projections on the backs of different types or kinds of sound boxes. The slotted portions 22^b and 23^b of the apertures 22 and 23 respectively, are preferably like each other in shape and size, except as modified by the different diameters of the circular portions communicating therewith, and they are likewise in axial alinement with each other when the trays are superposed in operative position. The height of the connecting web 11 is made substantially equal to the thickness of the main portion of a sound box casing, so that when a sound box 24 or 25 is placed between the tray members 9 and 10 with the circular projection on the back thereof within the circular portion 22^a or 23^a as the case may be, of the apertures 22 and 23 respectively, the back of the sound box will rest squarely against the upper surface of one of said tray members and the other tray member will rest squarely against and around the flange 24^d or 25^d which projects upwardly from the diaphragm 24^e or 25^e

mounted in the sound box 24 or 25 below the said rim or flange 24^d or 25^d.

By reason of this construction, the tray members are adapted to hold the article firmly between them, when placed within the outer container 1, to prevent the displacement of the article, and to keep the article spaced from and out of contact with the inner walls of the outer container 1.

In Fig. 2 is illustrated a sound box 24 having a circular projection 24^a extending from the back thereof, the projection 24^a being tube-like and adapted to fit over the end of the tone arm of a talking machine. This projection 24^a is shown to be of a size to snugly fit into the circular portion 23^a of the aperture 23 of the tray member 10. When this sound box is so placed between the tray members 9 and 10, the stylus bar 24^b enters and lies within the aperture 22 in the tray member 9 and the stylus bar mounting 24^c where it projects above or below the sound box casing lies within the slotted portions 22^b, 23^b, of the apertures 22 and 23 respectively, out of contact with the tray and below the top of the flanges 12 and 17 of the tray members respectively.

In Fig. 3 is shown another type or style of sound box 25 having a different sized circular projection 25^a on the back thereof, larger than the projection 24^a on the sound box 24. This sound box is similarly mounted within and between the tray members 9 and 10, the larger cylindrical projection 25^a fitting within the circular portion 22^a of the aperture 22. In this case the tray member 10 lies on the flange 25^d on the front face of the sound box casing 25 above the diaphragm 25^e and the stylus bar 25^b lies within the aperture 23 of the tray member 10. In a like manner, the stylus bar mounting 25^c where it projects above or below the sound box casing, lies and is securely held within the slotted portions 22^b and 23^b of the apertures 22 and 23 respectively. It must be apparent, then, that two sound boxes having cylindrical projections on the rear or back thereof of different sizes, are equally well accommodated by the single tray by fitting the projection into the aperture adapted to cooperate therewith, whereupon the stylus bar thereof projects into the aperture in the other member adapted to fit around the tubular projection in the back of another kind of sound box.

The free ends of the flanges 12 and 17 are preferably beveled as at 12^a and 17^a respectively, to facilitate the insertion of the tray into the outer box or casing 1.

The over-all width and length of the tray members are respectively made equal to the width and length of the interior of the box casing 1, and the combined height of the flange 12 and the web 11 and the flange 17 is equal to the height of the interior of the

outer box or casing 1 so that when the tray members, with a sound box secured between them, are inserted into the outer box or casing 1 the whole structure is very rigid, 5 the rigidity of the sound box casing itself resting between the tray members 9 and 10 being imparted to the whole structure, it being observed, however, that the stylus bar and stylus bar mounting and the diaphragm, 10 all of which are sensitive or delicate parts easily disarranged or broken, are well protected and are kept out of contact or engagement with the sides of the outer box or container 1 or the tray by the flanges 12 and 17, and by the apertures 22 and 23 in 15 the tray.

To unpack the sound box, the flaps 5, 3 and 4 are opened thus exposing the portion of the flange 12 or 17 (as the case may be) 20 formed by the flaps 15 or 20 respectively. This flange may be readily grasped between the fingers and the tray easily drawn out of the outer box or casing 1 without tearing or otherwise mutilating the outer box or the 25 tray members, or injuring the sound box.

As above stated, the outer box or container 1 is preferably made of sheet material, such as cardboard or box-board, but it is obvious that any light box construction 30 may be employed, because of the rigidity imparted to the outer casing by the tray and sound box carried thereby. The tray is also preferably made of card or box board, as has been above described, but any suitable sheet material may be used therefor. 35 My invention is, however, particularly adapted to the use of a normally flexible and relatively weak material, which, by reason of the construction and arrangement of the parts, as above described, is rendered 40 strong and rigid, and capable of withstanding the rough usage to which shipping boxes or cases are ordinarily subjected.

Having thus described my invention, 45 what I claim and desire to protect by Letters Patent of the United States is:

1. In a shipping case the combination with an outer casing, of a tray adapted to fit within said casing and comprising two 50 tray members disposed substantially parallel to each other, adapted to lie flat against the opposite sides of an article placed between them, and provided with apertures, one of which is adapted to fit snugly around 55 and frictionally hold said article within said member, a rectangular web connecting said tray members along one edge of each and forming a common stiffening flange for both members, and outwardly extending flanges on the free edges of each of said 60 trays to further stiffen said members, to respectively engage the walls of the outer casing, and to hold said article spaced from the walls of said outer casing.

65 2. In a packing case the combination of

an outer container, of an article holding means therein comprising a sheet of material bent over along two parallel scores or creases to form two parallel sheets connected at one edge by a rectangular web or flange, adapted to receive the article to be packed therebetween and provided with an opening in which said article is inserted and frictionally retained, the free margins of 70 said parallel sheets being bent at right angles to said sheets outwardly from said sheets and connected together to form a continuous flange to hold the article between said sheets and spaced from the inner walls of 75 said outer container.

3. In a shipping case for sound boxes of talking machines, the combination with an outer casing, of a tray adapted to fit within said outer casing and comprising two tray members stiffened along one edge of each thereof by a connecting web or flange and spaced from each other and disposed parallel to each other, and provided with alined apertures, one of which is adapted to 80 snugly receive the projection on the back of 85 a sound box, said members being each also stiffened along the other edges thereof by an outwardly extending continuous flange to hold a sound box between them out of contact with the said outer casing.

4. In a shipping case for sound boxes of talking machines, the combination with an outer casing, of a tray adapted to fit within said outer casing and comprising two tray members and a rectangular web or flange 90 connecting said tray members at one edge of each thereof to impart rigidity or stiffness to said edges, said tray members being spaced from each other and disposed parallel to each other, and provided with alined apertures, one of which is adapted to 95 snugly receive the projection on the back of a sound box, said members being adapted to 100 respectively lie against the opposite sides of a sound box, and each member being also stiffened by an outwardly extending continuous flange integral therewith and operative to hold said sound box spaced from the inner walls of said outer casing.

5. In a packing case or container for a 115 sound reproducer, the combination with an outer box or casing, of a tray comprising a sheet of material bent over along two parallel scores therein to form two parallel rectangular tray members spaced by a 120 web connecting said members along an edge thereof, each member being provided with an outwardly extending continuous vertical flange on the three free edges thereof, each member being also provided with an aperture within which is held the projection on the back of a sound box, whereby the aperture in one of said parts is adapted to provide space around the projecting portions 125 of said sound box when the said projection 130

thereof is snugly fitted into the aperture in the other member.

6. In a container for sound boxes, the combination with an outer rectangular casting and a tray fitting within said outer casting, said tray comprising two tray members and a web connecting said tray members at one edge thereof and forming a flange for both of said members, said tray members being provided each with an outwardly extending flange continuous along the free edges of said members, and beveled at the ends thereof.

7. In a container for sound boxes, the combination with an outer rectangular casting and a tray fitting within said outer casting, said tray comprising two tray members, and a web connecting said tray members at one edge thereof and forming a flange for both of said members, said members being also provided with substantially circular openings in axial alinement, each of said openings being provided with a radial slot of less width than the diameter of said circular opening, said slots being also in axial alinement with each other, said tray members being provided each with an outwardly extending flange continuous along the free edges of said members, and beveled at the ends thereof.

8. In a container for sound boxes, the combination with an outer rectangular casting and a tray fitting within said outer casting, said tray comprising two tray members, and a perpendicular web connecting said tray members at one edge thereof and forming a flange for both of said members, said

members being also provided with substantially circular openings in axial alinement, but of different diameters, each of said openings being provided with a radial slot of less width than the diameter of said circular opening, said slots being also in axial alinement with each other, said tray members being provided each with an outwardly extending perpendicular flange continuous along the free edges of said members, and beveled at the ends thereof.

9. A tray comprising two parallel spaced tray members, a relatively perpendicular web connecting said members along one edge of each thereof, said members each having an outwardly extending relatively perpendicular flange along the free edges thereof, said members being provided with alined openings with enlarged ends, said ends being of different sizes and respectively adapted to snugly fit around the projections on the backs of sound boxes.

10. A tray comprising two parallel spaced tray members, a web connecting said members along one edge thereof, said members having each an outwardly extending relatively perpendicular flange along the free edges thereof, said members being provided with alined keyhole shaped openings, the large circular ends of which are of different diameters adapted to snugly fit around the circular projections on the backs of sound boxes.

In witness whereof, I have hereunto set my hand this third day of March, 1921.

CLARENCE S. WICKES.
